UNITED STATES PATENT OFFICE.

CHARLES OSWALD, OF NEWARK, NEW JERSEY.

DESIGN FOR A SATCHEL OR BAG.

SPECIFICATION forming part of Design No. 20,819, dated June 9, 1891.

Application filed April 21, 1891. Serial No. 389,842. Term of patent 14 years.

To all whom it may concern:

Be it known that I, CHARLES OSWALD, a citizen of the United States, residing at Newark, in the county of Essex and State of New Jersey, have invented and produced a new and original Design for Satchels or Bags; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Referring to said drawings, Figure 1 represents an end elevation, and Fig. 2 a side elevation, of a satchel or bag, showing my design. These views are thought to be sufficient to fully illustrate the same.

The leading feature of my design consists in the peculiar configuration presented in the ends of the satchel or bag, in which the central portion *a* of the said ends is crescent-shaped, the extremities *b* of the crescent terminating a little above the hinge-joint of the satchel, as shown in the drawings. The design being thus located, a further description of the satchel is not deemed essential.

What I claim is—

The design for a satchel or bag herein shown and described.

In testimony that I claim the foregoing I have hereunto set my hand this 4th day of April, 1891.

CHARLES OSWALD.

Witnesses:

OLIVER DRAKE,
OSCAR A. MICHEL.
